UNITED STATES PATENT OFFICE.

AUGUST WOLLBRANDT, OF OAKLAND, CALIFORNIA.

BOX AND BARREL TRUCK.

1,202,948.

Specification of Letters Patent. Patented Oct. 31, 1916.

Application filed January 17, 1916. Serial No. 72,399.

To all whom it may concern:

Be it known that I, AUGUST WOLLBRANDT, a citizen of the United States, residing at Oakland, in the county of Alameda and State of California, have invented certain new and useful Improvements in Box and Barrel Trucks, of which the following is a specification.

The present invention relates to an apparatus for lifting and moving objects, especially barrels, boxes, and the like, and has for its object the provision of a manually operated device of the described class, by means of which one man may easily and quickly lift and move about, from place to place, objects of great weight.

The device is intended to take the place of the usual two-wheeled hand truck, the use of which necessitates the tipping or partial lifting of the object to place it upon the truck, and careful balancing thereof during the moving operation. No such tipping or partial lifting of the object is required in the use of the apparatus embodying the present invention, for the reason that said apparatus is provided with semi-automatic devices for engaging, lifting and supporting the object, by means of which an object of great weight may be raised several inches with comparatively little physical effort on the part of the operator.

In order to comprehend the invention, reference should be had to the accompanying sheets of drawings, in which—

Fig. 1 is a plan view of the device, certain parts being broken away and others shown in section for the sake of clearness. Fig. 2 is a partly broken longitudinal section taken on the line $x-x$ of Fig. 1, and viewed in the direction of the arrows. Fig. 3 is a partly broken transverse section taken on the line $y-y$ of Fig. 1, and viewed in the direction of the arrows. Fig. 4 is a part sectional detail view, enlarged, of the upper end of the steering head. Fig. 5 is a diagrammatic view of the barrel engaging devices and their operating means.

In the drawings, and referring particularly to Figs. 1, 2 and 3 thereof, the numeral 1 designates a substantially U-shaped horizontally disposed frame, carried upon two wheels 2 at the rear and one swiveled wheel 3 at the front thereof. Parallel to the side members 1' of said frame, and located inside thereof and spaced therefrom, are inner frame members 4. Plates 5 cover the space

between said inner and outer side frame members. The central space between the inner frame members 4 is of sufficient width to accommodate the largest barrel, box, or other object which the truck is designed to carry. 60

Adjacent to the inner face of each inner frame member 4 is a vertically disposed plate 8, adapted for vertical movement, and held in position by vertical bars 9 connected at 65 10 to said plate 8, and extending down through apertures 11 in the cover plate 5 and lying behind, or adjacent to the outer face of said inner frame member 4. The lower ends of these vertical bars 9 are united 70 by a horizontal member 12 having formed in its lower surface recesses 13, Fig. 2 of the drawings, adapted to ride upon a pair of eccentric cams 14 located between the frame members 1' and 4, and pivoted upon pins 15 75 secured to said frame members.

The eccentric cams 14 are rotated by lever-arms 16, connected by upwardly extending links 17 to bell-crank 18 fulcrumed at 19 upon a fixed plate 20 secured to and 80 extending upwardly from the side frame member 1', and said bell-crank are connected by a horizontal forwardly extending link 21 to one end of a cross bar 22, and preferably further connected thereto by a 85 brace 22'. The other arm of the U-shaped frame 1 carries a set of mechanism identical with that described above, and connected to the opposite end of the cross bar 22. The center of said cross bar is pivotally connected at 23, Figs. 2 and 4 of the drawings, to the short arm 24 of a bell-crank, the other arm 25 of which is extended a sufficient distance to form a handle, not shown in the drawings, by means of which the principal 90 functions of the truck are performed. Thus by raising the handle bar 25 from the position shown in Fig. 2 of the drawings, the links 21 are moved rearwardly, the eccentric cams 14 are rotated, through the bell-crank 95 18 and the links 17, to the left, and the structures comprising the vertical plates 8 and the bars 9 are thereby lowered. Each 100 of said structures carries a set of movable jaws or dogs, preferably four in number. The upper two dogs 26 are pivotally connected at 27, Figs. 2 and 3 of the drawings, to the upper ends of the vertical bars 9; the lower dogs 26' are loosely keyed in apertures 28 in the plate 8, and are permitted to have both pivotal and vertical 105 sliding movement therein. Each upper dog

105

110

26 is connected to the lower dog 26' in vertical alinement therewith by a jointed link 29, and said upper dogs 26 project through elongated apertures 30, Figs. 1, 2 and 5 of the drawings, in a horizontal bar 31, said bar 31 being carried by pivoted links 32 and 33 mounted upon the inner frame members 4, in such manner that fore and aft movement of said bars 31 causes 10 the same to be raised and lowered, by changing the inclination of the links 32 and 33.

The forward links 33 are fixed at their lower ends upon a transverse rock-shaft 34, the center of which is connected, through a 15 lever 35 and a link 36, Fig. 2 of the drawings, to a hand lever 37. Thus it will be seen that movement of the hand lever 37 rocks the shaft 34, which raises and lowers the horizontal bar 31, and, by the engagement 20 of the dogs 26 therewith, also raises and lowers the free ends of said dogs. The lower dogs 26' are, of course, moved substantially in unison with the upper dogs 26 by the jointed links 29.

25 When it is desired to lift and carry a barrel, box or other similar object upon the truck, said truck is backed up so that it straddles the barrel, which then occupies the position indicated by the numeral 38 in 30 Figs. 1, 3 and 5 of the drawings. The handlebar 25 is then raised, to lower the plates 8 and the dogs 26 and 26' carried thereby. The hand lever 37 is then moved rearward, to lower the free ends of said dogs to permit 35 the same to engage the sides of the barrel 38, as shown in Fig. 5 of the drawings, and indicated in dotted lines in Fig. 3. The handle bar 25 is then lowered again to its horizontal position to raise the plates 8, and 40 the barrel 38, being engaged by the dogs 26 and 26', is thereby lifted and its weight entirely supported by the truck, which can then be wheeled about as desired.

45 For moving objects that cannot be engaged by the dogs 26 and 26', a removable floor plate 39, Figs. 1 and 3 of the drawings, is provided for the space between the side frame members, and which rests upon inwardly extending flanges 40 formed at the 50 lower edges of the lifting plates 8. When said plates are in their lowermost position, the floor 39 is very close to the ground, and the object may be placed thereon with comparatively little effort. Said floor plate 39, 55 with the object thereon, is raised by means of the handle bar 25, as described above, to clear the ground, and the truck may then be moved about as in the previous case.

The handle bar 25, with its perpendicular 60 lever arm 24, is pivoted at 41, Figs. 2 and 5 of the drawings, upon the upper end of the post 42 which carries the forward wheel 3, and which is rotatably mounted in the truck frame at 43, Fig. 2. A swivel joint is 65 interposed at 44, which is in vertical aline-

ment with the rotatable post 42 when the handle bar 25 is in its horizontal position, so that the truck may then be moved and guided by means of said handle bar. When the handle bar 25 is raised, to lower the lifting mechanism, the swivel 43 and 44 are thrown out of line, and the post 42 is locked against rotation.

70 The invention has herein been described and illustrated in its preferred form. It is 75 obvious, however, that changes may be made in the form and construction of the device, without involving the essential principles of the invention. I therefore do not wish to limit myself in this regard, but on the contrary, I wish to be understood as claiming the invention as broadly as the state of the art will permit.

Having thus described my invention, what I claim as new and desire to protect by Letters Patent is:—

1. A device for the described purpose comprising a bifurcated frame, vertically movable lifting means mounted thereon, a plurality of dogs carried by said lifting means 90 and adapted to grip the sides of and support an object positioned between the arms of said frame, and mechanism for operating said lifting means.

2. A device for the described purpose comprising a bifurcated frame, movable lifting means mounted thereon, a plurality of shiftable dogs carried by said lifting means, mechanism for operating said lifting means, and devices for operating said dogs to cause the 100 same to engage the sides of an object positioned between the arms of said frame.

3. A device for the described purpose comprising a bifurcated frame supported upon wheels, one of which is carried by a 105 horizontally rotatable steering head; a steering handle carried by said head; a plurality of shiftable dogs associated with said frame and operable to engage the sides of an object positioned between the arms thereof; 110 and means connected with said steering handle for raising and lowering said dogs and the object engaged thereby.

4. In a device for the described purpose having a bifurcated frame, a vertically movable member carried by each arm of said frame, a plurality of dogs pivotally connected with said members and extending inwardly therefrom, means for adjusting said dogs relative to said members to cause them to engage the sides of an object positioned between the arms of said frame, and means for moving said members to raise and lower said object.

5. In a device for the described purpose 12 having a bifurcated frame, a plurality of upwardly inclined dogs projecting inwardly from the arms of said frame, means for adjusting the inner ends of said dogs to cause them to engage the sides of an object posi- 13

tioned between the arms of said frame, and means for bodily raising said dogs and the object engaged thereby relative to said frame.

5. 6. In a device for the described purpose having a bifurcated wheel-supported frame, one wheel thereof being mounted upon a swivel and provided with a handle for steering, a vertically movable member carried by each arm of said frame; means connected with and operated by said steering handle for raising and lowering said mem-
- 10

bers; and a plurality of inwardly projecting dogs carried by each of said members, said dogs being adapted to grip the sides of an object positioned between the arms of said frame.

In testimony whereof I have signed my name to this specification in the presence of two subscribing witnesses.

AUGUST WOLLBRANDT.
